UNITED STATES PATENT OFFICE.

BENJAMIN MASSETH, OF KARNS CITY, PENNSYLVANIA.

DRILLING-PACKER FOR OIL-WELLS.

SPECIFICATION forming part of Letters Patent No. 367,824, dated August 9, 1887.

Application filed January 29, 1887. Serial No. 235,849. (No model.)

To all whom it may concern:

Be it known that I, BENJAMIN MASSETH, of Karns City, in the county of Butler and State of Pennsylvania, have invented a new and useful Improvement in Drilling-Packers for Oil-Wells; and I do hereby declare the following to be a full, clear, and exact description thereof.

My invention relates to an improvement in the construction of oil and gas wells and in packing devices used therein. It is illustrated in the accompanying drawings, in which—

Figure 1 is a side elevation of the entire packing device, including an upper and a lower packer. Fig. 2 is a longitudinal axial section showing the upper packer and the tool which I use in packing both packers. Fig. 3 is a similar section showing the lower packer.

Like symbols of reference indicate like parts in all of the figures.

Heretofore in drilling deep wells it has been customary, after drilling below the fresh-water veins, to insert a string of casing, so as to shut off the water. The tools are then inserted within this casing, and a hole of less diameter is drilled down to a point below the salt-water veins. A second string of casing is then let down into the well, extending from the top of the well within the first casing to the bottom of the hole. This casing confines the salt-water and excludes it from the hole below. The remainder of the well is drilled down below the second casing by tools let through it. The disadvantage of this method of drilling is that it requires the use of a large amount of casing, and by reason of the fact that the second casing extends from below the salt-water veins entirely to the top of the well any gas which may be produced between these points and which might otherwise be utilized is wasted.

In the practice of my invention, after drilling to a point below the fresh water and having cased it off, I drill again to a point below the level of the salt-water, as before described. I then insert into the hole a sufficient number of casing-sections to extend from the bottom of the hole to a point just above the salt-water. These sections are provided with two packing devices, one at the base and the other at or near the top, and when these packers are set the salt-water is confined between them. Instead of the rubber packer at the base, the casing may be otherwise sealed at that point—for

example, by means of sediment placed at the bottom of the hole, the casing being driven into the sediment. The hole is then drilled down through the packed casing-sections as much farther as may be desired. The packing-casing then rests on and is supported by a ledge at its base, and is therefore very firmly held in place, and by reason of the fact that it only extends a little above the level of the salt-water it is of comparatively small weight and expense. By reason of the fact, also, that the packer does not extend up to the level of the ground it affords an unobstructed exit for gas escaping above the salt-water.

I shall now describe the construction of the apparatus which I prefer to use in the practice of this method of drilling, and shall first describe the upper packer, and shall then proceed to the description of the lower packer and the mode of adjusting both packers.

In the drawings, 2 represents a section of the oil-well casing. The upper packer consists of two rubber tubes, 3 and 4. The lower tube, 4, is fitted within the mouth of a collar, 5, which is screwed to the casing 2, and a follower, 6, interposed between the casing and the end of the packer, where it fits within the collar 5, serves to hold the packer in place. The upper end of the tube 4 is interiorly beveled or flared. The upper packer-tube, 3, fits loosely around the casing 2, and at its lower end is conical or wedge-shaped and fits within the flared mouth of the ring 4. Above the ring 3, and resting on its squared upper edge, is a lead ring, 7, which fits loosely around the casing 2.

8 is a conical wedge having a hollow cylindrical bore. At the lower end it fits around the casing 2, and is secured thereto by means of screw-threads 9. These screw-threads are few in number or shallow, so that they may be easily broken by jarring on the wedge 8. The widest part of the wedge 8 is uppermost, and its outer surface is preferably provided with a series of upwardly-directed annular teeth or ridges, b. The function of the wedge 8 is to expand the packing-rings in the manner which I shall hereinafter describe. Its upper end is thickened and provided with a seat, as at c, for the operation of the jarring tools.

14 is a ring made of cast-iron or some other

easily-frangible material, which is set within in the recess between the ends of adjoining sections of the casing 2. It is to this ring that the tool by which the casing is lowered into 5 the well is attached. This tool is shown in Fig. 2. It consists of a stock, 18, whose upper end is threaded at *d* to adapt it to be attached to the string of drilling-tools. At the lower end of the stock there is a piece of tubing, 19, which is provided with an annular projecting flange or nut, *e*. This tubing is fitted within the ring, and the flange is on the under side of the ring. The flange thus supports all the sections of the packing-casing, and when 10 the stock is secured to the drilling-tools it affords means whereby the whole apparatus may be lowered into the well.

In order to provide for the passage of the apparatus through the water in the well-hole, 20 I perforate the tubing 19 with holes *f* above the flange *e* and above the ring 14. The water rushes through these holes when the casing is lowered, and so offers no obstruction to it. Near the top of the stock 18 is an annular 25 collar, 20, which is adapted to rest upon the top of the wedge 8 on the seat *c*. It is by means of this collar that the wedge is forced down to expand the packers.

I do not desire to limit myself to the peculiar annular shape of the ring 14, since any 30 frangible seat arranged in an analogous way inside the casing may be substituted.

I shall now describe the construction of the lower packer, which is also provided with two 35 packing-rings, 10 and 11. The upper packing-ring, 10, is secured to a collar, 12, which is screwed to the lower end of one of the sections of the casing, and is also screwed to the upper end of the casing-section next below. 40 The lower packing-ring, 11, is affixed to the upper end of a collar, 15, which is screwed to the section of casing 16 below the casing-section 2, and fits around it, as shown in the drawings. The collar 15 is loosely mounted 45 on the casing 2; but it is preferably provided with frangible wooden pins 17, which pass through the casing 2, the casing 16, and the collar 15, so as to hold these parts together firmly enough to enable the casing to be lowered 50 into the well, but not so firmly that they may not be broken by jarring. The lower end of the casing 2 is preferably provided with a shoulder, *g*, which is adapted to engage with the corresponding shoulder, *g'*, on the collar 15, and to hold the parts together if the pins should accidentally break.

The operation of the device is as follows: In order to pack the casing the tool 18 is first secured to the ring 14, and the casing is then 60 lowered into the well until its lowest section, 16, rests upon the bottom of the hole, as shown in Fig. 1. The lower packer is first adjusted. This is done by jarring upon the ring 14, (shown in Fig. 2,) and the effect of this jarring is to 65 break the wooden pins which connect the casing 2 with the collar 15, and to cause the casing 2, carrying with it the packing-ring 10, to

descend within the section 16 and within the collar 15. The action of the wedge-shaped end of the ring 10 upon the flared mouth of the ring 11 forces the latter outward against the side of the well, so as to pack it, as will be readily understood. After the packing is finished, the ring 14 is broken by jarring upon it with increased force. In order to pack the 70 upper packer it is necessary to break the connection between the wedge 8 and the casing 2. This is done by jarring upon the seat *c* at the upper end of the wedge sufficiently hard to break the thread 9. When this thread is broken, 75 further jarring upon the seat *c* will exert a downward pressure upon the ring 7 and will force the packing-ring 3 downward between the outside of the casing and the inside of the ring 4, so as to bulge the latter ring outward 80 against the side of the well. After a time the resistance of the ring 4 to the further descent of the ring 3 causes the lower end of the wedge 8 to enter the space between ring 7 and the outside of the casing 2. After spreading the 85 ring 7 the wedge 8 will enter, forcing itself between the ring 3 and casing 2, and will expand the ring 3 outwardly against the side of the well.

The packing produced by this device is very 90 solid and effective, and the use of the two rings in the upper and lower packers is of great benefit in producing this result. I do not desire to limit myself solely to the use of these 95 double packing-rings; nor do I claim them 100 specifically herein, since I have made them the subject-matter of a separate application for Letters Patent.

In packing wells I have found that there is danger of the packer-casing becoming displaced by reason of upward pressure of water and gas, and by reason of the fact that in drilling the tools are apt to loosen the casing by striking against it. To prevent this I have devised an arrangement of catches or dogs, 21, 105 which are pivotally set in recesses on the outside of the apparatus with their points uppermost. They are provided with springs 22 or like mechanism for projecting them. In lowering the packer-casing into the well these 110 dogs offer little or no resistance; but if any upward force be exerted on the casing the dogs will catch on the sides of the well and will prevent the casing from being raised.

The use of the lead ring 7 is of great importance, because it protects the upper edge of the ring 3 during the packing operation and enables the action of the jarring after the threads 9 are broken to be exerted in forcing the ring 3 within the ring 4 before the wedge 115 enters the space inside the packing-ring.

One of the principal features of advantage of the whole packer is that it can be packed by the ordinary drilling-tools and does not need the casing to be extended to the top of 120 the well to manipulate it.

I claim—

1. The method hereinbefore described of constructing deep wells, which consists in drill-

ing to a point below the level of the salt-water veins, then inserting a casing into the hole with its lower end below and with its upper end above the salt-water veins, sealing the 5 space between the casing and well both above and below the salt-water veins, and then drilling through this casing, substantially as and for the purposes described.

2. A packer for deep-well casings, consisting in the combination, with the casing, of an expansible packer-ring surrounding the casing, and a cone secured to the casing above the packer-ring by a frangible connection, 9, substantially as and for the purposes described.

15 3. A packer for deep-well casings, consisting in the combination, with the casing, of an expansible packer-ring, a cone mounted above the packer-ring, and a lead ring, 7, interposed between the cone and the packer- 20 ring, substantially as and for the purposes described.

4. The combination, with a packer and the casing to which it is applied, of upwardly-directed dogs pivotally mounted on the casing, 25 substantially as and for the purposes described.

5. The combination, with a packer and the casing to which it is applied, of upwardly-directed dogs pivotally mounted on the casing, and springs for projecting them outward, sub- 30 stantially as and for the purposes described.

6. The combination, with a packer-casing, of a packing-ring arranged on one section, 16, of the casing, and a cone for expanding the ring, mounted on another section, 2, of the cas- 35 ing, arranged to move telescopically on the sec-

tion 16, a frangible ring, 14, secured to the section 2, and a tool connected with the ring, whereby the casing is lowered into the well and is jarred, substantially as and for the purposes described.

7. In a packer-casing, a frangible ring, 14, secured therein, and a tool attached to the ring and having a perforated hollow portion extending above the ring, substantially as and for the purposes described.

8. In a packer-casing having an upper and a lower packer, a cone for expanding the upper packer, a frangible ring, 14, secured to the casing to afford means for expanding the lower packer, a cone for expanding the upper packer, 50 and a tool connected with the said frangible ring and having a shoulder which is arranged to bear on said cone, substantially as and for the purposes described.

9. The combination, with a packer-casing, 55 of a packing-ring arranged on one section, 16, of the casing, a cone for expanding the ring, mounted on another section, 2, thereof, which section 2 is arranged to move telescopically on the section 16, and a frangible connection, 50 17, uniting the said sections, substantially as and for the purposes described.

In testimony whereof I have hereunto set my hand this 12th day of January, A. D. 1887.

BENJAMIN MASSETH.
